(57) **CLAIM**

The ornamental design for an abrasive article with holes, as shown and described.

DESCRIPTION

FIG. 1 is a perspective view showing the new design for an abrasive article with holes, as shown;

FIG. 2 is a front view thereof;

FIG. 3 is a back view thereof;

FIG. 4 is a right and left side view thereof; and,

FIG. 5 is a top and bottom view thereof.

The broken lines in the drawings indicate the outer perimeter of the abrasive article and form no part of the claimed design.
